UNITED STATES PATENT OFFICE.

SIGMUND FEUST, OF NEW YORK, N. Y.

DRAWER-PULL.

SPECIFICATION forming part of Letters Patent No. 402,236, dated April 30, 1889.

Application filed December 22, 1888. Serial No. 294,406. (No model.)

To all whom it may concern:

Be it known that I, SIGMUND FEUST, a citizen of the United States, residing at New York, county of New York, and State of New York, have invented certain new and useful Improvements in Drawer-Handles, fully described and represented in the following specification and the accompanying drawings, forming a part of the same.

10 This invention relates to the construction of those handles which are used upon drawers and for similar purposes, it being the object of the invention to provide a handle which shall have the requisite degree of strength and 15 present a finished and attractive appearance, and at the same time can be produced at a cost much below that of the same class of handles of the same strength and appearance which are now in common use. These handles here- 20 tofore in use have, where it was not necessary that they should present a fine appearance, been made of iron; but in those cases where a better appearance was required they have been made either of brass, bronze, or some 25 higher grade of metal, or of iron and electroplated. The handles made of iron and finished by electroplating are objectionable, in that the plating necessarily wears off comparatively soon when the handle is put in use, 30 and thus destroys the appearance of the handle, and those handles which are made of brass and similar high grades of metal or composition have, as heretofore constructed, been so expensive as to preclude their use in many 35 cases.

The present invention consists of a drawer pull or handle the outer shell of which is made of a thin or comparatively thin sheet of brass, bronze, or other metal or composition 40 possessing the desired appearance, and the interior of which is composed of lead or other cheap metal which can be run into the shell, so as to fill the same and prevent it from becoming dented or collapsed, and at the same 45 time add to the strength of the handle.

The invention also consists in a handle made as above stated, and provided with a strengthening-rod of iron or other stiff but inexpensive metal, and passing through the 50 shell and embedded in the lead or other metal with which the shell is filled. By this means

a handle is produced having all the desirable qualities of those which are made entirely of brass or composition, and at the same time the cost of manufacture is so reduced as to 55 render the article available for use in a large number of cases where the brass or composition handles as now constructed are unavailable by reason of their cost.

A full understanding of the invention can 60 be best given by an illustration and a description of a handle embodying the same, and such description will therefore be given in connection with the accompanying drawings, in which—

65 Figure 1 is a view of a handle embodying the present invention, showing the same attached to the front of a drawer or other article. Fig. 2 is a longitudinal central section of the handle. Fig. 3 is a cross-section of the 70 same.

75 Referring to said figures, it will be understood that A represents the front of a drawer or other piece of furniture to which the handle is attached; B, the usual plate to which the handle is hinged, and C the handle proper. The handle is made of substantially the usual 80 bow form, having its ends turned inward to provide pintles by which the handle is hinged in eyes b, secured to the plate B.

85 The handle C is composed of a shell, a, which is formed of sheet-brass or bronze or other metal or composition of a high grade, according to the appearance it is desired to give to the handle. The sheet of metal or metal blank from which the shell a is formed is treated in any suitable manner to bring it to the required shape to form the shell. The shell may be struck up into the required form by dies or otherwise, the edges being then 90 united by soldering or brazing, or otherwise, or it may be formed in any other manner. Inserted within the shell thus formed is a rod, c, of iron or other stiff metal, which fills or substantially fills the shell at the pintles d, 95 and around this rod c there is run lead or other cheap metal or composition, f, which fills the entire shell and makes a solid handle. The rod c serves to give additional stiffness and rigidity to the handle; but in some cases 100 where great strength is not required it may be omitted and the entire shell filled with the

lead or other cheap metal *f*. In some cases in manufacturing the rod *c* may be placed in a suitable mold and the metal *f* cast around the rod, and afterward the shell *a* may be formed around the core by suitable dies.

The sheet metal which forms the shell or covering *a* of the handle, although comparatively thin, is yet of sufficient thickness to withstand all the wear that the handle will be subjected to in use, and will cause it to present for almost an unlimited time the same appearance that would be presented by a handle made entirely of the same metal of which the shell is composed. The lead or other metal run into the shell and forming the core or filling *f* sustains the shell and prevents it from collapsing or becoming dented by use, which would be the case if it were not sup-

ported internally. In some cases the rod *c* may extend beyond the shell *a* and form the 20 pintles *d*.

What I claim is—

A drawer pull or handle consisting of an outer shell or casing of sheet metal and a core or filling of baser metal than the said shell or 25 casing, the latter being compressed upon and depressed in ornamental or other designs into the core or filling, substantially as specified.

In testimony whereof I have hereunto set my hand in the presence of two subscribing 30 witnesses.

SIGMUND FEUST.
